BOTTLE OR SIMILAR ARTICLE

Stephan Leonce Raoul Gaston Buxin, Sevres, France, assignor, by mesne assignments, to Colgate-Palmolive
Company, New York, N.Y., a corporation of Delaware

Filed Nov. 2, 1962, Ser. No. 72,358

Claims priority, application France May 18, 1962

Term of patent 14 years

(Cl. D58—8)

Fig. 1

Fig. 2

FIG. 1 is a front elevational view of a bottle embodying my new design;

FIG. 2 is an end elevational view thereof;

FIG. 3 is a top plan view thereof; and

FIG. 4 is a cross-sectional view taken along line 4—4 of FIG. 1, showing flat to slightly rounded side walls and flat end walls.

The closure shown in broken lines in FIG. 1 is for illustrative purposes only.

The dominant features of my design reside in the portions shown in full lines.

The rear and end views which are not shown are the same as the respective front and end views which are illustrated.

I claim:

The ornamental design for a bottle or similar article, as shown and described.
